DESIGN FOR A COFFEE MILL

Richard L. Schuhmann, Louisville, Ky., assignor to American Duplex Company, Louisville, Ky., a corporation of Kentucky

Application April 15, 1943, Serial No. 109,977

Term of patent 14 years

To all whom it may concern:

Be it known that I, Richard L. Schuhmann, a citizen of the United States, residing at Louisville, in the county of Jefferson and State of Kentucky, have invented a new, original, and ornamental Design for a Coffee Mill, of which the following is a specification, reference being had to the accompanying drawing, forming a part thereof.

In the drawing:

Fig. 1 is a perspective view of a coffee mill showing my new design;
Fig. 2 is a front elevational view of Fig. 1;
Fig. 3 is an end elevational view, and
Fig. 4 is a top plan view thereof.

I claim:

The ornamental design for a coffee mill, substantially as shown.
